[57] **CLAIM**

The ornamental design for the combined extension and support for a fishing rod, as shown and described.

DESCRIPTION

FIG. 1 is a perspective view of a combined extension and support for fishing rod, showing my new design, the broken line showing of a reel and part of a rod is for illustrative purposes only and form no part of claimed design;

FIG. 2 is another perspective view thereof;

FIG. 3 is a top plan view, the bottom being plain and unadorned; and

FIG. 4 is a side elevational view, the opposite side being a mirror image thereof.

FIG. 1

FIG. 2

FIG. 3

FIG. 4
